CLAIM

We claim the ornamental design for a disc support for LED light bulb, as shown and described.

DESCRIPTION

FIG. 1 is a perspective view of a disc support for LED light bulb showing our new design;

FIG. 2 is a right side elevational view thereof;

FIG. 3 is a top plan view thereof; and,

FIG. 4 is a bottom plan view thereof.

The left side of the illustrated disc support for LED light bulb is not shown because it is a mirror image of the right side shown in FIG. 2.

Any broken line illustration in the drawing disclosure is not part of the design sought to be patented.
